UNITED STATES PATENT OFFICE.

MORRIS KORNBLOM, OF BROOKLYN, NEW YORK.

DESIGN FOR A COMBINED LAMP SHADE AND STAND.

Application filed March 8, 1922. Serial No. 1,083. Term of patent 7 years.

To all whom it may concern:

Be it known that I, MORRIS KORNBLOM, a citizen of the United States, residing in Brooklyn, county of Kings, and State of New York, and doing business at 284 Bay 11th Street, Brooklyn, New York, have invented a new, original, and ornamental Design for Combined Lamp Shade and Stand, of which the following is a specification, reference being had to the accompanying drawing, forming part thereof.

The figure is a view of the lamp shade and stand in perspective.

I claim:

The ornamental design for a combined lamp shade and stand as shown.

MORRIS KORNBLOM.
